[57] CLAIM

The ornamental design for a foot support, as shown and described.

DESCRIPTION

FIG. 1 is a rear perspective view of a foot support, showing my new design;

FIG. 2 is a rear elevational view thereof;

FIG. 3 is a front elevational view thereof;

FIG. 4 is a top plan view thereof;

FIG. 5 is a bottom plan view thereof, the broken lines on each end of the straps represent top-stitching;

FIG. 6 is a left side elevational view thereof;

FIG. 7 is a right side elevational view thereof; and,

FIG. 8 is a perspective view thereof, the broken line showing is for illustrative purposes only and forms no part of the claimed design.

FIG. 4

FIG. 5

FIG. 6

FIG. 7

FIG. 8
